UNITED STATES PATENT OFFICE.

JAMES A. BROGAN, OF LAWRENCE, MASSACHUSETTS, ASSIGNOR TO UNITED SHOE MACHINERY COMPANY, OF PATERSON, NEW JERSEY, A CORPORATION OF NEW JERSEY.

WELT-PREPARED MACHINE.

1,241,087.

Specification of Letters Patent. Patented Sept. 25, 1917.

Application filed October 24, 1913. Serial No. 797,025.

To all whom it may concern:

Be it known that I, JAMES A. BROGAN, a citizen of the United States, residing at Lawrence, in the county of Essex and State 5 of Massachusetts, have invented certain new and useful Improvements in Welt-Preparing Machines; and I do hereby declare the following to be a full, clear, and exact description of the invention, such as will enable others skilled in the art to which it 10 appertains to make and use the same.

The present invention relates to an improved machine for preparing welting for use in making welt shoes.

15 In preparing the welting for use in making shoes known to the trade as Goodyear welt shoes, a stitch-receiving groove is cut in the lower or flesh face of the leather and a bevel is cut on the inner edge of the upper 20 or grain face of the leather. According to the general practice heretofore, the groove has been cut by means of a grooving knife which operates to remove a small, half-round strip of leather from the flesh side 25 to form the groove, and the bevel has been cut by means of a beveling knife which operates to skive off the grain surface of the leather at the inner corner. A welt thus prepared has certain disadvantages. The thin 30 layer of grain fiber at the grain surface of the welt is the densest and strongest part of the leather. In beveling the welt by skiving off the grain surface, the grain fiber is cut away so that the inseam, which often passes 35 from the bottom of the groove through the skived surface of the welt, is supported only by the softer and weaker fibers forming the inner layers of the leather, and it is not infrequent for the inseam to be pulled through 40 the welt. Moreover, it often happens that in sewing the welt to the lasted shoe, the inseam will be sewed so near to the inner edge of the welt that the skived surface is partially visible in the crease between the upper 45 and the welt. Where blacked welting is used, the appearance of the lighter colored skived leather is particularly noticeable, and necessitates blacking the crease when the shoe is finished. The removal of the half-round strip of material in cutting the groove still further tends to weaken the portion of the welt which receives the inseam, and allows the stitches of the inseam to be more easily pulled through the welt.

50 The object of the present invention is to

provide a welt preparing machine of improved construction and mode of operation by which welting having a stitch receiving groove and beveled edge may be produced which will be free from the disadvantages 60 above referred to. With this object in view the present invention consists in a machine for preparing welting having devices and combinations of devices constructed and arranged to operate as hereinafter described 65 and particularly pointed out in the claims.

In the illustrated embodiment of the invention hereinafter specifically described both the groove and the bevel are formed in the welt by a molding operation without the 70 removal of any of the material of the welt, the formation of the groove being facilitated however by cutting a slit partially through the material at the place in the welt strip where the groove is subsequently molded. 75 It is understood however that the invention is not limited to the specific embodiment illustrated and that as regards the formation of the groove the invention is broad enough to include other forms of cut or the omission of the cut altogether.

The welt and the method of preparing the same described in this application are not claimed herein but form the subject-matter of applications Serial Nos. 878,176 and 85 878,177, filed December 19, 1914.

In the drawings, which illustrate the preferred embodiment of the invention, Figure 1 is a front elevation of the head of the machine for preparing the welting; Fig. 2 90 is a plan view of the machine; Fig. 3 is a plan view taken partly in section along the line 3—3 of Fig. 1; Fig. 4 is a vertical section taken along the line 4—4 of Fig. 3; Fig. 5 is a side elevation taken from the 95 right of Fig. 3 showing a detail of the machine head; Fig. 6 is a vertical section illustrating the operation of the first pair of molding rolls on the welting; Fig. 7 is a vertical section illustrating the operation of the 100 second pair of molding rolls on the welting; Fig. 8 is a section of the welt as it enters the machine; Fig. 9 is a section of the welt after the knife has cut a slit in its flesh side; Fig. 10 is a section of the welt after passing 105 through the first pair of molding rolls; and Fig. 11 is a section of the completed welt as it comes from the machine.

The welting is preferably a strip of leather of substantially rectangular cross 110

section and having a finished grain surface, as illustrated in Fig. 8. In the machine illustrated in the drawings, the welting is first softened or tempered in a moistening device 1, and is drawn past a slitting knife 2 which operates to cut a slit in its flesh face extending partially through the welt. From the slitting knife, the welt passes between a pair of molding rolls indicated generally by reference numeral 3 which operate to open and enlarge the slit cut by the knife and to mold the bevel on the inner margin of the grain face of the welt. From the pair of rolls 3, the welt passes to a second pair of molding rolls indicated generally by reference numeral 4 which operate to complete the enlargement of the slit into a stitch-receiving groove and to complete the formation of the molded bevel on the inner margin of the welt. As the welt leaves the machine, a deflector 5 molds or bends the welt laterally toward its inner or beveled edge so that, when the welting dries, it retains a permanent lateral deflection or bend.

25. The moistening device 1 by means of which the leather is tempered or softened so that it can be easily molded, is mounted on a bracket 10 at the right hand side of the machine. This moistening device consists of an open-topped, water-tight sheet metal box or tank 11 in which is held the roll of welting 12 to be prepared. This moistening tank 11 is semi-circular in shape and is narrow enough so that its front and rear walls loosely engage the sides of the roll of welting and prevent the welting from being drawn sidewise from the roll and becoming tangled. This sheet metal tank 11 is loosely supported in an open-topped, substantially semi-circular support or crib 13. The water in the moistening tank 11 is replenished from a supply tank 14 which is connected with it by means of a short supply pipe 15. The supply pipe 15 enters the storage tank 14 below the water level therein and, as the top of the tank 14 is closed and air-tight, the water flows into the tank 11 only when the water level of the moistening tank 11 drops below the supply pipe 15.

50. The moistening tank 11 is thus automatically supplied with water as needed. The rear wall of the crib 13 has a slot 16 to receive the supply pipe 15 so that the moistening tank 11 and storage tank 14 can be removed. The storage tank 14 is filled with water after it is removed by inverting it and pouring the water in through a bottom closure 17.

60. The tempered welting passes from the moistening tank over the work table 20, where it is operated upon by the slitting knife 2. The welt is guided and properly positioned beneath the knife 2 by means of a fixed front edge gage 21 and an adjustable rear edge gage 22 which may be ad-

justed for different widths of welting. The knife 2 is a thin, circular cutting knife mounted on a hub 23 which fits over the end of the knife shaft 24 and is secured thereon by means of a set screw 25. The shaft 24 rotates in a direction to cause the knife 2 to cut against the direction of movement of the welt. The set screw 25 may be loosened and the knife may be adjusted longitudinally of the shaft 24 in order to vary the position of the slit cut in the welt. The knife shaft 24 is journaled in a bearing 26 formed on the end of a horizontal arm 27 which is hinged at 28 to the machine head. Pinned to the rear end of the knife shaft 24 is the driven member of an Oldham coupling 30. The driving member of the Oldham coupling is formed on the front face of a gear 31 mounted on a bearing shaft 32 in the machine frame. The gear 31 is driven by means of an idle gear 33 which meshes with a gear 34 carried by the lower roll of the pair of rolls 3. The Oldham coupling 30 allows the knife shaft 24 to be raised or lowered a limited amount with relation to 90 the driving gear 31.

The movable knife shaft bearing 26 is pressed upwardly by means of a helical compression spring 40 mounted in a recess in the bottom of the bearing 26 and pressing 95 against the top of the back gage 22. The knife bearing 26 is pressed downwardly against the spring 40 to bring the knife 2 into operative position for engagement with the welt by means of a screw stud 41 threaded in a boss in the top of the bearing 26, which is engaged by a cam on the belt shipper rod 42. When the belt shipper rod 42 is drawn forwardly, as shown in the drawings, to shift the driving belt 43 from the 100 loose pulley 44 to the fast pulley 45, the head of the stud 41 is engaged by the flat face 46 of a riser or cam formed on the bottom of the belt shipper rod, and the knife is depressed into the position shown in Fig. 5 110 of the drawings, so that it slits the welt. When the belt shipper rod 42 is moved backwardly to shift the belt from the fast to the loose pulley, the recess or cut-away portion 47 on the bottom of the rod 42 comes over 115 the top of the stud 41 and permits it to rise under the action of the spring 40 which also raises the knife into an inoperative position above the welt. By adjusting the screw stud 41, the depth of the slit in the welt 120 may be varied. A lock nut 48 is provided for locking the screw stud 41 in position. By means of the above described connection between the knife and belt shipper, the knife is automatically brought down into operative 125 position when the machine is started, and is automatically raised into inoperative position when the machine is stopped so as to offer no obstruction to the introduction of a fresh piece of welting into the machine. 130

A finger guard 50 protects the knife 2 and safeguards the operator when introducing a fresh strip of welting into the machine.

The welt, as it enters the machine, is shown in cross section in Fig. 8. In Fig. 9, a cross section of the welting after it has been operated upon by the slitting knife 2 is shown. The slitting knife cuts in the welt the slit indicated at 51 in Fig. 9.

10 The welting passes from the knife 2 along the work table 20 and between the pair of rolls indicated generally by reference numeral 3. This pair of rolls comprises upper and lower rolls 60 and 61, respectively.

15 These rolls are splined upon roll shafts 62 and 63 respectively. The ends of the lower shaft 63 are journaled in the front and back upright plates 64 and 65 of the machine head. Fast on the rear end of the shaft 63

20 is a gear wheel 66 which meshes with a gear wheel 67 carried by the driving shaft 68 of the machine. The shaft 62, which bears the upper roll 60, is journaled in front and rear boxes 70 and 71 which have a limited ver-

25 tical adjustment in the side plates 64 and 65. The bearing boxes 70 and 71 are vertically adjusted by means of adjusting screws 72 and 73 so that the rolls 60 and 61 may be adjusted and rigidly spaced with relation

30 to each other. The upper roll 60 is driven by means of a gear 74 fixed to the rear end of the roll shaft 62 and meshing with the gear 66 on the lower roll shaft, so that the two rolls 60 and 61 are both positively driven at the same speed.

35 The manner in which the rolls 60 and 61 coöperate to mold the welt is best illustrated in Fig. 6. The portion 80 of the roll which engages the greater part of the flesh face of

40 the welt is smooth and cylindrical. Near the forward end of the roll is an annular rib 81 which runs in and opens up the slit formed by the slitting knife. This rib has a substantially V-shaped cross section, the

45 point of the V being rounded. At the side of the rib 81 is formed a conical or inclined forwardly facing shoulder 82 which engages the flesh face of the welt between the groove and the inner edge. By "inner edge" is

50 meant the edge of the welt which is the inner edge when it is sewed in the shoe. Beyond the conical shoulder 82, the roll is reduced to form a flat, vertical forwardly facing shoulder 83. The lower roll 61 has a cylindrical portion 85 which bears against

55 the grain face of the welt opposite the cylindrical portion 80, the rib 81 and part of the shoulder 82 of the roll 60. At the front of the cylindrical portion 85 is a conical or 60 inclined, backwardly facing shoulder 86 which operates against the grain surface of the welt to bevel the inner corner of the welt. Beyond the shoulder 86, the roll is enlarged to form a flat, vertical, backwardly facing shoulder 87 which fits closely against

the forwardly facing shoulder 83 of the roll 60. The tight fit between the shoulders 83 and 87 prevents the possibility of the edge of the welt being pushed forwardly beyond the inclined shoulders 82 and 86. As 70 shown in Figs. 6 and 10, the rib 81 operates to open up or enlarge the slit 51 cut by the slitting knife. The rib 81 does this by compressing the leather at the sides and bottom of the slit and forms the partially completed 75 stitch-receiving groove indicated at 88 in Fig. 10. The conical shoulders 86 and 82 co-operate to mold or deflect the inner edge of the welt to form the partially completed bevel 89, indicated in Fig. 10. 80

The welt is led from the first set of molding rolls to the second set of molding rolls through a welt guide which is made up of a bottom plate or table 90, a front edge gage 91, a top plate 92 and a rear edge gage 85 93. The bottom plate 90 extends across between the upright front and back plates 64 and 65 and is rigidly secured thereto. The front edge gage 91 is formed by an upstanding lip or flange on the front edge of the 90 bottom plate 90. The back edge gage 93 is formed by a forwardly facing shoulder on the bottom of the top plate 92. In order to adjust the back edge gage for welts of varying widths, the top plate 92 is mounted to 95 have a limited horizontal movement and is adjusted in position by means of a thumb screw 94 threaded through the front upright plate 64 of the machine frame. The right hand ends of the bottom and top plates 90 100 and 92 are beveled so that these plates project between the rolls 60 and 61 to engage and properly guide the end of the welt strip as it emerges from between these rolls.

The second pair of rolls indicated generally by reference numeral 4 comprises upper and lower rolls 100 and 101, respectively. These rolls are mounted similarly to the first pair of rolls, the upper roll 100 being mounted on a roll shaft 102 which is 105 journaled in bearings 105 and 106 vertically adjusted by means of the screws 107 and 108, and the lower roll 101 being mounted upon a roll shaft 103 journaled in fixed bearings. The roll shafts 102 and 103 are 110 provided with meshing gears 104 and 109 and are driven from the gear 67 on the driving shaft of the machine. The upper roll 100, like the upper roll 60, has a cylindrical portion 110, a rib 111, a conical shoulder 112 115 and a forwardly facing flat shoulder 113. The rib 111 is somewhat larger than the rib 81 and is substantially U-shaped in cross section. The lower roll 101, like the lower roll 61, has a cylindrical portion 115, a conical shoulder 116, and a rearwardly facing flat shoulder 117. The rib 111 operates to 120 still further enlarge the slit formed by the slitting knife into the half-round stitch-receiving groove indicated at 118 in Fig. 11. 130

The conical shoulders 116 and 112 coöperate to complete the bevel 89 partially molded by the first pair of rolls and form the completed bevel 119, as shown in Fig. 11.

5 The welt passes from the second pair of molding rolls through a welt guide which comprises bottom and top plates 130 and 131 and a back gage. The top plate 131 is a continuation of the top plate 92. The back 10 gage consists of a shoulder 132 on the lower part of the top plate 131 and a deflector 133 engaging the edge of the welt as it passes from the shoulder 132. The deflector 133 is hinged at 134 to the top plate 131 and is 15 adjusted to bend the welt more or less by means of an adjusting screw 135. A spring 136 serves to hold the deflector 133 against the end of the screw 135. The deflector 133 molds the welt by deflecting or bending it 20 laterally toward its inner edge. The leather is tempered so that it is easily molded and permanently retains this deflection. The welt thus transversely bent toward its inner edge more nearly conforms to the curvature 25 of the shoe than does a straight welt and is, therefore, more easily sewed.

The operator takes the tightly wound roll of welting 12 and drops it into the moistening tank 11, the water in which quickly permeates and tempers the leather. Assuming that the machine is idle, the shipper rod 42 is in its rearward position and the slitting knife 2 is raised above the work table. The operator takes the free end of the welt and 30 pushes it over the work table 20 into engagement with the first pair of rolls. Then the operator draws the shipper handle forward, depressing the knife 2 and starting the machine. The end of the welt is seized 35 by the first pair of rolls and is thereafter fed through the machine until the entire strip is grooved and beveled, whereupon the operator stops the machine. It will be seen that the short length of welting (about two 40 inches) at the front end of the welt strip, which lies between the slitting knife 2 and the feed rolls when the machine is started, is not slit by the knife. The action of the feed rolls upon this short, unslit length is to 45 press in it a groove which very closely resembles the groove formed throughout the rest of the length of the strip where the material is slit before passing between the molding rolls. Although the groove formed 50 in the short length of welting at the end of the welting is not quite as good as the groove formed by the conjoint action of the knife and rolls, nevertheless, it is good enough so that this short, unslit length of welting can 55 be used, and there is, therefore, no waste to the strip.

In the usual type of welt preparing machines now in use the welt is dragged past the grooving and beveling knives by the feed 60 rolls. This puts a strain upon the strip be-

tween the knives and the feed rolls and often results in breaking the welt strip at its lapped joints. In the machine of the present invention, the slitting knife exerts very little drag upon the welt strip and the molding of the groove and bevel takes place between the rolls which feed the welt, and consequently there is no danger of pulling apart the lapped joints of the welting.

The completed welt, as shown in Fig. 11, 75 has the inseam-receiving groove 118 of substantially the same form as that heretofore formed by means of a grooving knife. Instead of forming the groove by cutting out the material, the present machine operates 80 to displace the material which was cut out by the old method, the material which is displaced from the groove being forced under pressure into the body of the welt. Instead of skiving off the material at the inner margin of the grain face as heretofore done, this material is displaced under pressure to form the bevel. The displacement of the material at the bevel causes a consolidation 85 of the leather and also causes the inner margin to be displaced angularly or bent toward the flesh face of the strip. The operation of molding the groove in the welt serves to compress or consolidate under pressure the fibers of the leather thus strengthening the 90 material forming the walls of the groove, instead of weakening the welt. The action of the shoulders 86 and 116 is also to compress or consolidate the leather through which the inseam stitches pass and so strengthen it to 100 better withstand the strain of the inseam. The inner edge of the welt, which, in the methods of grooving and beveling heretofore employed, has been weakened by the removal of material, is, in the illustrated embodiment 105 of the present invention, not weakened. As shown in Fig. 11, the grain surface of the leather extends along the bevel to the extreme inner edge of the welt so that the entire face of the bevel is covered by the grain 110 fiber of the leather. Although it may be desirable for the entire bevel to be faced with grain fiber, it is not necessary as long as the grain fiber surface of the leather extends far enough over the bevel to support the inseam. It is within the contemplation of the present invention to have the grain fiber surface extend only partially over the entire surface of the bevel. In the illustrated embodiment of the invention, the 115 bevel 119 shown in Fig. 11 has a flat grain surface which is inclined to the plane of the welt. The present invention, however, is not limited to its illustrated embodiment. As for example, shoulders 82, 86, 112, and 120 116 on the rolls of the machine may be so shaped that the bevel 119 may have a convex face. The important thing is to have the inner margin of the grain side of the welt 125 deflected toward the flesh side of the welt to 130

form an inclined shoulder which fits against the upper of the lasted shoe. The term "bevel", as used in the claims is, therefore, intended to be a term of description rather than limitation and to include within its purview the marginal shoulder on the grain surface of the welt strip whether it has a flat face like that illustrated in the drawings, or whether it has a curved face. Inde-
5 scribing the welt, the term "upper face" is intended to refer to the face of the welt which lies uppermost and is visible in the completed shoe, and the face which is usually the grain surface of the leather. The term "under face" is applied to the face of the welt which lies against the outsole. The "inner edge" of the welt is the edge which is sewed to the upper and insole in the completed shoe.
10

20 While the preferred embodiment of the present invention has been illustrated and described, it is to be understood that the present invention is not limited to its preferred embodiment, but may be embodied in other constructions within the scope of the invention as set forth in the following claims:—

1. A machine for preparing welting for use in the manufacture of welt shoes having, 30 in combination, a plurality of coöperating pressing members for successively acting on a welt strip for progressively displacing the material under pressure on the under face of the welt strip near the inner edge to form a longitudinal stitch-receiving groove, and for molding the material under pressure at the inner margin of the upper face of the welt strip to form a bevel at the inner margin of the upper face, substantially as de-
35 scribed.
40

2. A machine for preparing welting for use in the manufacture of welt shoes having, in combination, a knife for making a cut in the under face of the welt strip near the inner edge extending partially through the material, and a plurality of coöperating pressing members for successively acting on a welt strip for enlarging the cut into a stitch-receiving groove by compressing the material at the sides and bottom of the cut, substantially as described.
45

3. A machine for preparing welting for use in the manufacture of welt shoes having, in combination, a knife for making a cut in the under face of the welt strip near the inner edge extending partially through the material, means for enlarging the cut into a stitch-receiving groove by compressing the material at the sides and bottom of the cut and means for molding under pressure the material at the inner margin of the upper face of the strip to form a bevel at the inner margin of the upper face, substantially as described.
55
60

4. A machine for preparing welting for

use in the manufacture of welt shoes having, in combination, a knife for making a cut in the under face of the welt strip near the inner edge extending partially through the material, means for enlarging the cut 70 into a stitch-receiving groove by compressing the material at the sides and bottom of the cut, and means operating simultaneously with said enlarging means for molding under pressure the material at the inner 75 margin of the upper face of the strip to form a bevel at the inner margin of the upper face, said enlarging and molding means coöperating to consolidate under pressure the material between the groove 80 and bevel through which the inseam is sewed, substantially as described.

5. A machine for preparing welting for use in the manufacture of welt shoes having, in combination, a plurality of coöperating 85 pressing members for successively acting on a welt strip for progressively displacing the material under pressure on the under face of the welt strip near its inner edge to form a longitudinal stitch-receiving groove 90 therein, and simultaneously with said displacing operation for molding under pressure the material at the inner margin of the upper face of the strip to form a bevel at the inner margin of the upper face, said displacing and molding members acting to consolidate under pressure the material between the groove and bevel through which the inseam is sewed, substantially as de- 95 scribed.
100

6. A machine for preparing welting for use in the manufacture of welt shoes having, in combination, means for molding the welting under pressure to form a longitudinal stitch-receiving groove in its under face 105 near the inner edge and to form a bevel at the inner margin of its upper face, and means for laterally deflecting or bending the welt strip toward its inner edge, sub-
110

7. A machine for preparing welting for use in the manufacture of welt shoes having, in combination, means for tempering the welt strip, means for molding the tempered material to form a longitudinal stitch-re- 115 ceiving groove in the under face of the strip near the inner edge, and means thereafter operating upon the tempered material for permanently bending the strip comprising a deflector for molding or deflecting the strip laterally toward its inner edge, sub-
120

stantially as described.
8. A machine for preparing welting for use in the manufacture of welt shoes having, in combination, a knife for making a 125 cut in the under face of the welt strip near the inner edge extending partially through the material, and a pair of coöperating rolls between which the strip is passed under pressure, one roll having an annular rib entering 130

and enlarging the cut to form a stitch-receiving groove and the other roll having a shoulder bearing against the inner margin of the upper face to mold a bevel thereon, substantially as described.

9. A machine for preparing welting for use in the manufacture of welt shoes having, in combination, a knife for making a cut in the under face of the welt strip near 10 the inner edge extending partially through the material, and a pair of rolls between which the strip is passed under pressure, one roll having an annular rib for entering and enlarging the cut into a stitch-receiving 15 groove and having an inclined shoulder engaging the under face of the strip between the cut and its inner edge, the other roll having an inclined shoulder coöperating with the shoulder on the first roll and bearing 20 against the inner margin of the upper face of the strip to mold a bevel thereon, substantially as described.

10. A machine for preparing welting for use in the manufacture of welt shoes having, in combination, a knife for making a 25 cut in the under face of the welt strip near the inner edge extending partially through the material, a pair of rolls between which the strip is passed under pressure, one roll 30 having an annular rib entering and enlarging the cut to form a stitch-receiving groove and the other roll having a shoulder operating against the inner margin of the upper face of the welt strip to form a bevel 35 thereon, and a second pair of rolls operating on the welt after it has passed through the first pair of rolls, one of said second pair of rolls having an annular rib entering and further enlarging the cut, the other of said 40 second pair of rolls having a shoulder operating against the inner margin of the upper face of the strip to further mold the material and complete the bevel commenced by the first pair of rolls, substantially as 45 described.

11. A machine for preparing welting for use in the manufacture of welt shoes having, in combination, a knife for making a cut in the under face of the welt strip near 50 the inner edge extending partially through the material, and a plurality of pressure rolls each having an annular rib for entering and progressively enlarging the cut to form a stitch-receiving groove, substantially as described.

12. A machine for preparing welting for use in the manufacture of welt shoes having, in combination, a welt guide, a cutting knife for making a cut in the under face 60 of the welt near its inner edge extending partially through the material, power driven means for feeding the welt, and means for throwing on and off the power having connections with the knife for placing it in operative position when the power 65

is thrown on and for placing the knife into inoperative position when the power is thrown off, substantially as described.

13. A machine for preparing welting for use in the manufacture of welt shoes comprising a plurality of pairs of rolls between which the welting is passed under pressure, one roll of each pair having an annular rib operating against the under face of the welt strip near its inner edge for displacing and compressing the material to form a stitch-receiving groove in the under face, substantially as described. 70 75

14. A machine for preparing welting for use in the manufacture of welt shoes, having, in combination, means for making a cut in the under face of the welt strip near its inner margin, extending partially through the material, and a plurality of compressing means arranged to operate in succession to progressively enlarge the cut into a stitch receiving groove by compressing the material at the sides and bottom of the cut, substantially as described. 80 85

15. A machine for preparing welting for use in the manufacture of welt shoes, having, in combination, a plurality of coöperating pressing members acting successively on a welt strip to mold under pressure the material of the strip to form a bevel at the inner margin of its upper face, substantially as described. 90 95

16. An edgewise bending machine for leather, comprising a pair of feed rollers having parallel axes for feeding the leather strip between them and acting on the strip for its full width, an intake guide bearing against the edge of the leather strip on the intake side of the rollers, and a bending guide bearing against the same edge of said leather strip on the discharge side of the rollers, said bending guide being displaced toward the leather strip from that plane perpendicular to the axes of the rollers which contains the intake guide. 100 105 110

17. An edgewise bending machine for leather, comprising a pair of feed rollers having parallel axes for feeding the leather strip between them, an intake guide bearing against the edge of the leather strip on the intake side of the rollers, a bending guide bearing against the same edge of said leather strip on the discharge side of the rollers, said bending guide being displaced toward the leather strip from that plane perpendicular to the axes of the rollers which contains the intake guide, and means for permitting the varying of the relative positions of said two guides axially of the rollers. 115 120

18. An edgewise bending machine for leather, comprising a pair of feed rollers having parallel axes for feeding the leather strip between them, an intake guide bearing against the edge of the leather strip on 125 130

the intake side of the rollers, and a bending 5
guide bearing against the same edge of said
leather strip on the discharge side of the
rollers, said bending guide being displaced
toward the leather strip from that plane
perpendicular to the axes of the rollers
which contains the intake guide, said bending
guide being pivotally mounted so that it
can be adjusted to different positions rela- 10
tive to the aforesaid plane.

19. An edgewise bending machine for
leather, comprising a pair of feed rollers
having parallel axes for feeding the leather
strip between them, an intake guide bearing
15 against the edge of the leather strip on the

intake side of the rollers, a bending guide
bearing against the same edge of said
leather strip on the discharge side of the
rollers, said bending guide being displaced
toward the leather strip from that plane 20
perpendicular to the axes of the rollers
which contains the intake guide, and mem-
bers coöperating with the two faces of the
leather strip at the bending guide to pre- 25
vent buckling of the leather as it is oper-
ated on by said bending guide.
